United States Patent Office

Des. 221,093
Patented July 6, 1971

221,093

ACCESSORY FOR TOY TOP

Anthony D. Miller, Torrance, Calif., assignor to Mattel, Inc., Hawthorne, Calif.

Filed Mar. 25, 1970, Ser. No. 22,045

Term of patent 14 years

Int. Cl. D21—02

U.S. Cl. D34—15

FIG. 1

FIG. 2

FIG. 3

FIG. 4

FIG. 5

FIG. 6

FIG. 1 is a perspective view taken from the top of an accessory for toy top embodying my design;

FIG. 2 is a perspective view taken from the bottom;

FIG. 3 is a side view thereof;

FIG. 4 is a side view similar to FIG. 3 but rotated 45° about its longitudinal axis;

FIG. 5 is a top view thereof; and

FIG. 6 is a bottom view.

I claim:

The ornamental design for an accessory for toy top, as shown.
